CLAIM

The ornamental design for a pattern stitching for a palm portion of a work glove, as shown and described.

DESCRIPTION

FIG. 1 is a front perspective view of a pattern for stitching for a palm portion of a work glove showing my new design; FIG. 2 is a front elevational view thereof;

FIG. 3 is a left side elevational view thereof;

FIG. 4 is a right side elevational view thereof; and,

FIG. 5 is a top plan view thereof.

The broken line showing of the glove in FIGS. 1, 2, 3, 4, and 5 is for illustrative purposes only and forms no part of the claimed design.
